DESIGN FOR A PLATE OR THE LIKE

Marcelline Gouglar, Chicago, Ill., assignor to Castleton China Incorporated, New York, N. Y., a corporation of New York

Application October 8, 1943, Serial No. 111,304

Term of patent 14 years

To all whom it may concern:

Be it known that I, Marcelline Gouglar, a citizen of the United States of America, residing at Chicago, in the county of Cook and State of Illinois, have invented a new, original, and ornamental Design for a Plate or the like, of which the following is a specification, reference being had to the accompanying drawing, forming part thereof. Fig. 1 is a top plan view of a plate, showing my new design and Fig. 2 is a cross-sectional view thereof, taken along line 2—2 of Fig. 1 and in the direction of the arrows.

I claim:

The ornamental design for a plate or the like, as shown.

MARCELLINE GOUGLAR.
